UNITED STATES PATENT OFFICE.

GEORGE WEST, OF SYRACUSE, NEW YORK.

PLASTER-MIXING MACHINE.

SPECIFICATION forming part of Letters Patent No. 392,652, dated November 13, 1888.

Application filed November 11, 1887. Serial No. 254,945. (No model.)

To all whom it may concern:

Be it known that I, GEORGE WEST, of Syracuse, county of Onondaga, in the State of New York, a citizen of the United States, have invented certain new and useful Improvements in Mixing-Machines, of which the following is a specification, reference being had to the accompanying drawings, in which—

Figure 1 is a side elevation of my machine. Fig. 2 is a central vertical longitudinal section thereof. Fig. 3 is an end elevation of same; and Fig. 4, a vertical transverse section looking toward the end upon which the driving-gear, &c., is mounted.

Similar letters and figures of reference indicate corresponding parts throughout the several views.

My invention relates to machines for mixing dry ingredients or materials; and my object is to produce a machine which will do its work perfectly and quickly and will deposit the mixture in bags without any handling of the material except putting it into the feed-hopper.

It consists in the novel construction and arrangement of the component elements, as hereinafter described, and specifically set forth in the claim hereto annexed.

It is constructed as follows:

A is a stationary cylinder supported horizontally upon the legs 1.

B is the mixing-cylinder inclosed within cylinder A.

C is a feed-hopper outside of the cylinder A and communicating with the interior of cylinder B through opening 2. The slide 3 regulates the feed, and it is operated by the rack 4 on lower face of slide and the pinion 5 engaging with the rack, the pinion-shaft being provided with an ordinary hand-wheel (or handle) outside of the hopper to rotate the pinion.

D is the main shaft, suitably mounted in bearings and having on one end the screw-conveyer 6 and upon the other end the necessary gearing, pulleys, belt, and clutch mechanism, mounted, substantially as shown in Figs. 2 and 3, to rotate the main or beater shaft in one direction and the revolving cylinder in an opposite direction, as indicated by arrows in Figs. 3 and 4 of the drawings.

Upon the end of the mixing-cylinder I secure the sleeve 7, through which the shaft D

passes, and upon the aforesaid sleeve mount the gear 8, and the rotation of this gear rotates the cylinder through its belt and gear connection to the main drive-shaft. 55

Within the cylinder B and upon the main shaft I adjustably secure the screw arms or beaters 9 10 alternately, so that the screw action of beaters 9 is reversed by that of beaters 60 10, thus more thoroughly stirring, disintegrating, and mixing the materials. I also provide the inner surface of the cylinder B with the ordinary longitudinal shelves or wings, 11, which carry up material from the bottom and 65 shower it down onto the top of the mixture and beaters, thus aiding in the mixing. I also provide the cylinders A B with man-holes in the usual manner. I also provide cylinder B with one or more spring doors or gates, 12, opening 70 inwardly and arranged longitudinally or otherwise, and to operate them I pivotally connect to cylinder A the curved trackway 13, the free end of which is beveled, as shown; and 14 is a hand-lever pivotally mounted, its inner 75 end bearing against or connected to the trackway.

On the outside of the cylinder B, I mount a series of buckets, 15, which rotate with it and the extremities of which are contiguous to the 80 inner surface of cylinder A, which scrape and carry upward the deposited material lying on the bottom of the cylinder A as they revolve around, and as soon as said buckets pass by the perpendicular center of the cylinder the carried material is precipitated into the trough E, (hereinafter described,) said buckets being mounted longitudinally upon the outer surface of the rotating cylinder B, substantially as shown. 85

E is a trough opening into the cylinder A to receive the mixed material, provided with a series of openings, 16, in its bottom, and 17 is a sliding frame connected to the operating-rod 18, upon which frame I place the cut-offs 95 19, (shown of pyramidal form,) using one-half as many cut-offs as openings, and bag-spouts 20 connected to them, so that one-half of the openings are always open, and when one set of bags is full I push in or pull out the slide 100 and cover those and deflect the material into the other set of openings.

By the operation of the lever 14 I raise or depress the trackway 13, so that the pivoted

dog 26 is thrown into or out of engagement with the gate 12, and when in engagement it opens the gate so long as the dog is in contact with the trackway, as shown in Fig. 4 of the drawings. The aforementioned operating lever 14 is, when thrown above or below a horizontal line, held in proper position by the weight or pressure of the pivoted trackway upon its engaging end.

10 It will be observed from the foregoing that no stoppage in the revolution of the cylinder B is necessitated in order to allow of the precipitation of the mixed material into the trough, &c., and therefore the operation of my machine is (aside from the feeding of the unmixed ingredients into the hopper) practically continuous.

15 It will further be observed that by throwing the mechanism for rotating the cylinder out of gear I can still rotate the wings or blades, and the rotation of said wings with the gates open will blow out and clean out the mixing-cylinder in case I desire to change the ingredients of the mixture.

My improved mixing-machine is, primarily, 25 intended to operate upon wall-plaster in a dry state.

What I claim as my invention, and desire to secure by Letters Patent, is--

20 In a mixing-machine, the combination of 30 the rotating beater-shaft, a rotating cylinder having a spring-door, and a pivoted dog engaging said door mounted on said cylinder, an inclosing stationary cylinder, an adjustable trackway pivoted at one edge to the stationary 35 cylinder, and a lever pivoted to the stationary cylinder and engaging the free edge of the said trackway for the purpose of adjusting the same, substantially as described.

25 In witness whereof I have hereunto set my hand this 7th day of May, 1887.

GEORGE WEST. [L. S.]

In presence of--

WM. C. RAYMOND,
PARKE W. WICKS.
